UNITED STATES PATENT OFFICE.

JOEL F. TERRIL AND WALLACE SIMONSON, OF OWOSSO, MICHIGAN.

CASTER.

SPECIFICATION forming part of Letters Patent No. 352,209, dated November 9, 1886.

Application filed September 30, 1885. Renewed June 25, 1886. Serial No. 206,271. (No model.)

To all whom it may concern:

Be it known that we, JOEL F. TERRIL and WALLACE SIMONSON, of Owosso, in the county of Shiawassee and State of Michigan, have invented certain new and useful Improvements in Casters; and we do hereby declare the following to be a full, clear, and exact description of the invention, such as will enable others skilled in the art to which it appertains to make and use the same.

Our invention relates to an improvement in casters.

Hitherto it has been customary to construct ball-casters by providing a metallic chamber of sufficient depth to receive a little more than one-half the ball, and to continue the metal upwardly to form a socket adapted to receive the reduced end of the leg, the end of the leg resting on the top of the metallic chamber, and the whole being secured to the leg by a transverse screw or pin, or simply by wedging the end of the leg into the socket. The result has been to cause undue strain on the end of the leg, the ball being located wholly below it, and when the bearing has become worn it has rendered the caster as a whole useless.

The object of our present invention is to provide a caster which will admit of the ball being placed to a considerable extent within the end of the wooden leg, and which will furnish a convenient and effective means for securing the cap to the leg without exposing the fastening screw or pin to view.

A further object is to provide a caster which shall be ornamental, and in which the part subject to the greatest wear can be replaced at a slight expense, and which shall be quite inexpensive.

With these ends in view our invention consists in certain features of construction and combinations of parts, as will be hereinafter described, and pointed out in the claim.

In the accompanying drawings, Figure 1 is a view of the caster applied to a leg angular shaped in construction. Fig. 2 is a bottom plan view, and Fig. 3 is a vertical section, through the center of the ball.

A represents the wooden leg of a table or

any other article of furniture to which a caster is commonly applied. In the end of the leg is formed a hemispherical chamber, B, in which a similarly-shaped shell of metal, b, is fitted. A thick plate of metal, C, of the same shape as the end of the leg is provided with a central perforation adapted to fit a narrow zone of the ball located between a great circle thereon and a parallel circle the thickness of the plate C therefrom. The edges of the plate C are turned up to fit and embrace the sides of the leg, as shown at D, and the plate C and sides D combine to form a cap for the end of the leg.

The cap C D may be formed by pressing a sheet of metal into the described shape; or it may be formed by soldering the plate C to a plate shaped to form the sides D; or a thin sheet of metal may be pressed into the shape C D and re-enforced by a thick plate the shape of the end of the leg soldered to the inside of the plate C. The sides D are cut at the top into ornamental shapes, as shown at d, and to complete the ornamental effect we provide a finishing-edge, E, embracing the leg a short distance above the top of the side D, and provided with depending points or other similar ornamental design.

For the purpose of securing the cap C D to the leg, the plate C is provided near its four corners with screw-holes F, countersunk to bring the heads of the screw flush with the bottom of the plate.

The ball-roller G having been placed in position within the shell b, the cap C D locks it securely in place. The ball G should be made of some hard wood—lignum-vitæ, for example—or it may be formed of metal, in which case the wear upon the shell b would be of slight consequence, as the shell could be renewed at a trifling cost.

The leg may be round or oval or any desired angular shape in cross-section, and the cap be fitted thereto with the same advantages as in the rectangular form shown.

Having fully described our invention, what we claim as new, and desire to secure by Letters Patent, is—

The caster consisting, essentially, of the

hemispherical shell set in the end of the leg, the ball-roller, and the cap with its perforated end plate and ornamental sides, said cap being provided with perforations through the end plate, adapted to receive fastening-screws, substantially as set forth.

In testimony whereof we have signed this

specification in the presence of two subscribing witnesses.

JOEL F. TERRIL.
WALLACE SIMONSON.
